Primary Examiner — Ricky Pham(74) *Attorney, Agent, or Firm* — The Van Winkle Law Firm; William G. Needy(57) **CLAIM**

The ornamental design for a soufflé dish, as shown and described.

DESCRIPTION

FIG. 1 is a perspective view of a soufflé dish, showing my new design;

FIG. 2 is a front elevational view thereof;

FIG. 3 is a rear elevational view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof.

In the drawings, the broken lines showing a lid in FIG. 8 form no part of the claimed design.
